UNITED STATES PATENT OFFICE.

ALEXANDER THOMAN, SR., OF ARKONA, ONTARIO, CANADA.

LOCATING-BUOY.

1,096,966.

Specification of Letters Patent.

Patented May 19, 1914.

Application filed October 28, 1912. Serial No. 728,131.

To all whom it may concern:

Be it known that I, ALEXANDER THOMAN, Sr., a subject of the King of Great Britain, resident of the town of Arkona, county of Lambton, Province of Ontario, in the Dominion of Canada, manufacturer, have invented certain new and useful Improvements in Locating-Buoys; and I hereby declare that the following is a full, clear, and exact description of the same.

The invention relates to improvements in a locating buoy as described in the present specification and illustrated in the accompanying drawings that form part of the same.

The invention consists essentially in the novel construction and arrangements of parts whereby the buoy is formed to carry compartments for valuables and adapted to float in deep and shallower water.

The objects of the invention are to devise a form of buoy which will be a very good locator and at the same time preserve valuables either in the form of money, jew-
elry or documents, so that they may be picked up by locating vessel, and generally to provide a comparatively inexpensive and yet very durable device.

In the drawings Figure 1 is a perspective view of the device complete supported in its deck cradle. Fig. 2 is a vertical sectional view of the buoy. Fig. 3 is a horizontal sectional view looking upward. Fig. 4 is a perspective detail of the safe deposit compartments. Fig. 5 is a perspective detail of cap closing in the top of the buoy. Fig. 6 is a perspective detail of one of the cable reels.

Like numerals of reference indicate corresponding parts in each figure.

Referring to the drawings, 1 are the side walls arranged in the form of a pyramid, joined together by the outside seams 2 and terminating at the upper end preferably in the upstanding flanges 3, surrounding a square opening, said seams projecting outwardly at each corner, so as to strengthen the construction and at the same time be a means of warding blows off said side walls.

4 are holes in said seams 2, whereby the handling of the buoy is facilitated.

5 is the base of the buoy, formed up preferably from one piece of metal in the shape of a rectangular receptacle, and joined at the tops of its side walls to the lower ends of the side walls, the side walls of said base

flaring slightly from the bottom, so that said base is slightly tapered.

6 are warding irons rigidly secured in pairs to two opposite sides of the base and turning under the bottom of said base and projecting above said sides of the base.

7 is a safe deposit box having a number of compartments 8 in the form of drawers 8 the box being of such dimensions as to be inserted through the opening surrounded by the flanges 3 and fit snugly to said flanges. This safe deposit box may be in any form desired, the main feature being for the buoy to contain some valuables and means for storing them.

9 is a cap of rectangular form having its side walls fitting closely over the flanges 3 and slightly curled out at the lower end 10 to shed the water washing over the buoy.

11 is a lock securing the cap to the buoy and of any suitable pattern.

12 are lugs secured to the base 5 adjacent to the corners thereof and supporting the chains 13 and 14, the latter being crossed.

15 is a closed loop embracing the chains 13 and 14 at the crossing and having a swivel eye 16 at the lower end which is connected to the anchor chain or cable 17.

In very deep waters simply a weight 18 is attached to the cable which is adapted to locate somewhere about the place where the ship goes down, but it preserves the valuables. In shallower waters it is anchored to the ship by the chain or cable.

19 are the uprights of the deck cradle supported on the feet 20, which are screwed to the deck and intermediate of their height bent outwardly to receive the base 5, the said uprights 19 being connected at the under portions by the rails 21 and at their upper portions by the plates 22 said rails 21 being connected to one pair of uprights and said plates 22 connecting another pair of uprights.

23 is a wire connecting the tops of the uprights 19 of the cradle to increase its stability.

24 and 25 are reels journaled in the rails 21 and wound up by a crank handle or other means, said reels carrying the anchoring cables, which are of different lengths to suit different depths of water, these cables being preferably measured off in feet by the tags 27. One of these cables is connected to the buoy and the other end preferably secured to a flange wheel at one end of a reel. The

reels 24 and 25 are of any suitable construction but the most convenient is, as shown in the detail view, in which one of the flanges 28 is attached to the inner shaft 29 and the other flange 30 is loose.

In the use of this invention the cradle, as explained in the foregoing is screwed firmly to the deck of the vessel and in time of danger, the safe deposit box is removed after 10 taking off the cap, and all valuables are then placed within said box. This safety receptacle could also be used under ordinary conditions as a protection against petty theft, etc. The box is then placed in the buoy and 15 the cap is firmly locked in place and in the case of shallower waters the suitable cable for the depth of water is attached. When the ship goes down the buoy will float out of the cradle and the cable will unwind from 20 the particular reel and indicate the location of the ship as well as preserve the valuables. In the deeper waters the buoy will simply float to the top and if within a reasonable time another ship comes along the buoy will 25 serve to indicate the direction of drift of boats, rafts or bodies as well as preserve the valuables. This locating buoy might under ordinary circumstances be housed on ship, in a cabin on deck, said cabin or room having a

floating roof which would admit of the buoy 30 remaining on the surface of the water as the ship sinks. This is merely mentioned as one way of housing buoy but any means suitable to users can be employed.

What I claim is:—

1. A locating buoy comprising a base in the form of a substantially rectangular floating receptacle, side walls upstanding from said base in pyramid form and terminating in upstanding flanges surrounding an opening, a safe deposit box vertically arranged in said buoy and extending upwardly through said opening, and a cap fitting over said flanges and closing said opening. 40

2. A locating buoy comprising a base in 45 the form of a floating receptacle of substantially rectangular form, side walls in the form of a pyramid and extending upwardly from said base and converging to an opening at the other end and joined together by 50 outstanding seams, having holes therethrough, and a cap closing said opening.

Signed at Arkona this 4th day of Sept. 1912.

ALEXANDER THOMAN, SR.
